UNITED STATES PATENT OFFICE.

JOHN A. COOPER, OF JERSEY CITY, AND WILLIAM R. VAN BUSKIRK, OF PATERSON,
NEW JERSEY.

WATER-GAGE.

1,003,236.

Specification of Letters Patent. Patented Sept. 12, 1911.

Application filed May 27, 1911. Serial No. 629,757.

To all whom it may concern:

Be it known that we, JOHN A. COOPER, a citizen of the United States, and a resident of Jersey City, in the county of Hudson and State of New Jersey, and WILLIAM R. VAN BUSKIRK, a citizen of the United States, and a resident of Paterson, in the county of Passaic and State of New Jersey, have invented a new and Improved 5 Water-Gage, of which the following is a full, clear, and exact description.

This invention relates to a new and improved water-gage for determining the level in boilers or the like, and is especially 10 adapted for boilers on locomotives.

An object of this invention is to provide a new and improved water-gage for boilers, which will be strong and durable, and which will not be liable to blow out, and in which, 15 even if it should blow out, the fragments of glass would be caught by a protector, preventing them from flying and injuring the person or eyes of the engineer.

A further object of this invention is to 20 provide a water-gage with a protecting sleeve having one of its ends formed integral therewith, and with the feed-pipes projecting inwardly beyond the edge or ends, so as to protect the packing between 25 the sleeve and the glass tube.

These and further objects, together with the construction and combination of parts, will be more fully described hereinafter and particularly set forth in the claim.

30 Reference is to be had to the accompanying drawings forming a part of this specification, in which similar characters of reference indicate corresponding parts in all the views, and in which—

35 Figure 1 is a vertical section; Fig. 2 is a side view in elevation of the water-gage; and Fig. 3 is a horizontal section.

Referring more particularly to the separate parts of this invention as embodied in 40 the form shown in the drawings, 1 indicates the sheet of a boiler, to which the water-gage 2 is attached. Usual feeders 3 and 4 are provided for the water-gage, with control valves 5 and 6.

45 The water-gage includes a protecting sleeve or casing 7, shown in the form of a cylinder having diametrically opposite vertically-extending slots 8, the outer side edges

of which may be beveled at 8', and which are for the purpose of permitting light to 55 pass through the sleeve at these points, so that the water level can be read.

The sleeve 7 is provided at one end with a head 9, formed integral therewith, and at its opposite end with a head 10, detachably connected to the body of the sleeve in any suitable manner, as by means of a screw-threaded connection, indicated at 11. The heads 9 and 10 have screw-threaded openings, indicated at 12 and 13, through 60 which extend feed-pipes 14 and 15. Located within the protecting sleeve 7, there is provided a water glass tube 16, which is of suitable thickness so that it will not readily 65 wear out or break, and made of a glass of suitable strength and durability. The tube 16 bears at its upper and lower ends on packing rings 17 and 18, located between the ends of the glass tube and the heads 9 and 10.

70 It is to be noted that the feed-pipes 14 and 15 project into the glass tube 16 a considerable distance at each end, beyond the packing rings 17 and 18, so as to protect these packing rings from direct contact 75 with the steam or hot water from the boiler. The packing rings project on both sides of the tube, to allow for expansion. It will thus be seen that there is provided a simple, inexpensive water-gage, which will be 80 strong and durable, and which will protect the packing from direct contact with the water and steam.

85 While we have shown one embodiment of our invention, we do not wish to be limited to the specific details thereof, but desire to be protected in various changes, alterations and modifications which may come 90 within the scope of the appended claim.

Having thus described our invention, we 95 claim as new and desire to secure by Letters Patent:—

The combination with a cylindrical sleeve having a plurality of diametrically opposite slots, of heads at opposite ends of 100 said sleeve, one of said heads being detachably connected to said sleeve, said heads having openings therein, feed-pipes extending through said openings, a glass tube 105 extending into said sleeve, between said heads, and packing rings interposed be-

tween said glass tube and said heads, said feed-pipes projecting into said glass tube a considerable distance beyond said packing rings to keep said packing rings out of direct contact with steam and hot water coming into said tube.

In testimony whereof we have signed our

names to this specification in the presence of the subscribing witnesses.

JOHN A. COOPER.

WILLIAM R. VAN BUSKIRK.
